DESIGN FOR A SHOE SOLE

Walter H. Wirries, Lima, Ohio, assignor to The Lima Cord Sole and Heel Company, Lima, Ohio, a corporation of Ohio

Application April 26, 1939, Serial No. 84,560

Term of patent 14 years

To all whom it may concern:

Be it known that I, Walter H. Wirries, a citizen of the United States, residing at Lima, in the county of Allen and State of Ohio, have invented a new, original, and ornamental Design for a Shoe Sole, of which the following is a specification, reference being had to the accompanying drawing, forming a part thereof.

Figure 1 is a plan view of a shoe sole, showing my new design; and

Figure 2 is a cross-section on the line 2—2 of Fig. 1.

I claim:

The ornamental design for a shoe sole, as shown.
